TIMER OR THE LIKE

Theodore Ornas, Jr., Birmingham, Mich., assignor to The United States Time Corporation, Waterbury, Conn., a corporation of Connecticut

Application March 6, 1950, Serial No. 8,341

Term of patent 14 years

(Cl. D42—7)

To all whom it may concern:

Be it known that I, Theodore Ornas, Jr., a citizen of the United States, residing at Birmingham, in the county of Oakland and State of Michigan, have invented a new, original, and ornamental Design for Timer or the like, of which the following is a specification, reference being had to the accompanying drawing, forming part thereof.

Fig. 1 is a front elevational view of a timer or the like, showing my new design.

Fig. 2 is a side view thereof.

I claim:

The ornamental design for a timer or the like, substantially as shown.

THEODORE ORNAS, JR.
